DOUBLE IRONING TABLE

Charles W. Sadenwater, Saginaw, Mich., assignor
to Saginaw Manufacturing Co., Saginaw, Mich.,
a corporation of Michigan

Application June 5, 1937, Serial No. 146,632

1 Claim. (Cl. 38—136)

This invention relates to ironing tables of the kind known as double sleeve boards, characterized by having two oppositely facing boards, one narrower than the other and arranged to be collapsed flat together, or, when the table is extended, to be spaced apart parallel to each other, and to be kept in that position by supporting frames or bails connecting the two.

My present improvement is found in the construction and arrangement of the bails, and in a simple means on the bails for keeping the table in its raised position.

An object of the improvement is to cheapen the quantity manufacture of double sleeve boards by reducing the number of parts; and to make the bails of such shape that they not only pivot the boards together but also, when extended they automatically hold the upper board rigidly against racking tendency. This is done without employing any bolts, wing nuts or other fasteners. The table can not collapse under the conditions of ordinary use, yet can be folded by merely pushing the upper board forwardly in the direction of its length.

With these objects in view, my invention consists in the devices described in the specification and shown in the accompanying drawing, in which,

Fig. 1 is a view in perspective showing my sleeve ironing table, extended;

Fig. 2 is a side view of the table shown in Fig. 1;

Fig. 3 is a side view of the table after its parts have been moved from the position shown in Fig. 2 to approximately closed position; and

Fig. 4 is a perspective view showing one of the bails, and the staples by which the bail is hinged to the boards.

As is usual in such double sleeve tables, ironing boards 1, 2, are connected together by a pair of bails 3, 4, made of wire or rod material bent as shown in Fig. 4, the bails being spaced apart lengthwise of the board.

According to my improvement the mid portion 5 of each bail is pivotally secured, crosswise of the narrower board (1), by means of fasteners 6.

Axially aligned pintles 8, 8 project laterally outward from the ends of legs 7, 7, parallel with the member 5. They are pivotally secured to the under side of the wider board 2 by fastenings 9. The outer end portions of the pintles 8 are bent so as to extend forwardly at 10, 10 both in the same plane and at an acute angle to the plane of parts 5 and 7, said angles being

somewhat less than 90 degrees, preferably about 70 degrees, as is indicated at A in Fig. 2.

From its collapsed position, Fig. 3, the upper board 2 moves upwardly and rearwardly, that is, to the left, until the legs 7, 7 are off center relatively to the part 5 and the stop members 10 engage the board, as in Fig. 2. In that position the upper board 2 can be used for ironing and the board 1 serves as a base for the table. When ironing the upper board 2 is firmly held against racking motion by the members 10. They prevent board 2 and bails 3 and 4 from moving toward the left. The bails can not move forward, that is toward the right, because of the downward pressure of the working load. When the table is turned upside down, and the ironing is done on board 1 instead of board 2 the said rigidity is equally well maintained.

Heretofore, double sleeve boards were provided with bails having forwardly projecting feet 20 that engaged the face of a board, but such bails stood substantially perpendicularly to the board when extended. Consequently, bolts and nuts or other fastening devices were required to fix the bails in their working position. Such fastenings are eliminated by my improvement, with reduction in cost of manufacture.

My improvement is distinguished from such earlier devices in that each bail has its legs 7, 7 and members 10, 10, Fig. 2, disposed in two 30 planes which include between them the acute angle, A, whereby fastening of the table in its erected position is effected automatically.

As has been stated, the boards 1 and 2 are preferably of different widths and shape, adapting them to a variety of work.

The table is collapsed from the position shown in Fig. 2 to that of Fig. 3 by simply pushing the upper board to the right, in the direction of the straight arrow. The upper board 1 then follows 40 beyond the partly collapsed position indicated in Fig. 3 until it is completely closed and the boards 1 and 2 are compactly nested. If desired, however, the face of board 2 may be rabbeted or countersunk to receive the parts 5, thus leaving 45 the contiguous faces of the boards free of projections. If thus rabbeted, when the table is folded the right-hand ends of boards 1 and 2 come into contact with each other and can be used for pressing articles, for example, neck ties 50 and the like. The board can be packed in the bottom of a trunk or drawer, and the articles will be kept free from wrinkles. To enable the device to be thus used as a press the entire space between the boards should be practically free 55

from obstructions, and it will be noted that in my improved structure there are no lugs or nuts and bolts that project from the pressing area. The members 10 of bails 3 and 4 are spaced far enough apart so that when the table is collapsed, as in Fig. 3, they will be outside of the marginal edges of the narrower board 1. The entire area of the boards between members 10, 10 of bail 3 is thus kept available for pressing.

- 5 10 Having thus described my invention, what I claim and desire to secure by Letters Patent is:
A pair of elongated boards, bails between said boards and spaced apart lengthwise thereof, a mid portion of a bail being rotatably secured to
15 the inner face of one of said boards, leg portions

having outwardly directed pintles pivotally secured to the inner face of the other board, being spaced apart a distance greater than the width of the said first board and at points longitudinally spaced from the said mid-portion of the bail, the outer end portions of said pintles being directed lengthwise of the other board to present stops that lie flatwise against said other board when extended; the plane defined by said stops being at an acute angle to the plane defined by the legs, whereby the said spacing of the outer portions of the pintles allows the boards to be folded until they substantially touch each other.

CHARLES W. SADENWATER. 15
